UNITED STATES PATENT OFFICE.

JOHN W. DIXON, OF MAYWOOD, ILLINOIS.

MACHINE FOR MAKING METAL BINDING STRIPS.

Application filed October 16, 1924. Serial No. 743,867.

The machine of the present invention is designed for the purpose of automatically feeding a section or sheet metal to knives or cutters which successively sever from the edge of the sheet a series of metal strips, which are thereafter fed downwardly to a crimping blade which folds the metal strips in such a way as to produce a grooved or channeled strip which is thereafter used for the purpose of binding or edging a picture, calendar or the like.

The machine is an improvement on that shown and described in Patent No. 864,349 issued August 27, 1907, to Frederick William Yager, and in general design and construction the present machine follows quite closely the machine of the patent above referred to.

The special improvements are directed mainly to the following features:

1. To the mechanism for actuating the stop fingers which arrest the advance of the metal sheet preparatory to the severance of a strip therefrom by the knives or cutters;
2. To the means provided for adjusting the position of said stop fingers; and
3. To the means for operating the mechanisms which carry the severed strips from the knife to the point where the crimping blade is located.

Other features and details will appear from the description of the invention, which consists in the features of construction and combinations of parts hereinafter described and claimed.

In the drawings:

Figure 1 is an end elevation of the machine taken from the right hand end of the machine, as viewed from the front;

Fig. 2 is a similar view taken from the left hand end of the machine, as viewed from the front;

Fig. 3 is a sectional elevation of the machine looking toward the right end thereof;

Fig. 4 is a sectional detail showing the method of mounting and adjusting the stop fingers;

Fig. 5 is a plan view of the same mechanism;

Fig. 6 is a detail showing the power transmission mechanism for actuating the feeding chains which carry down the severed strips;

Fig. 7 is a sectional view taken through the gear and sprockets of Fig. 6; and

Fig. 8 is a detail of the reciprocating cutter frame partly broken away.

The machine as a whole is mounted upon a frame which comprises end standards 10-10, each comprising front legs 11 and rear legs 12, an upper cross rail 13 and a lower cross rail 14, and an upwardly extending supporting arm 15. The ends of the frame are connected by a lower transverse beam 16; and the arms 15, which extend obliquely rearwardly from the upper portion of the frame, afford a mounting for a diagonally disposed feeding table 17, upon which rests a wedge shaped platform 18 which serves as a support upon which the metal blank A is rested.

The ends of the frame are further provided with diagonally disposed forwardly extending arms 19, which furnish guides for the support and reciprocation of a clamping plate 20 and a movable cutter bar 21, which latter co-acts with a fixed cutter bar 22 secured to the lower edge of the feeding table 17, which cutter bars present their proximate or cutting edges to the same intermediate plane, so that the movable bar may slip past the edge of the fixed bar and sever from the metal blank so much thereof as protrudes beyond the cutting plane.

The down feeding of the metal blank is arrested by the provision of a bank of stop fingers 23, some of which are shown in Figs. 4 and 5. The fingers 23 are disposed at substantially right angles to the plane of the feeding platform, and each finger at its tip end is provided with a notch 24 which receives the lower edge of the metal blank.

Each finger on its lower edge near its center is provided with a notch 25 at which point the finger is fulcrumed upon the upper edge of an angle bar 26, which is carried by a pair of strap bars 27 which also serve to support a rear angle bar 28, which bar is provided in its front flange with a series of guide slots 29 within which the rear lower ends of the fingers are guided. This arrangement furnishes a frame for the entire bank of stop fingers, which frame is completed by the provision of an upper bridge bar 30 which overlies the rear ends of the fingers and is held in spaced relation

to the angle bar 28 by the provision of spacer bolts 31.

Each of the fingers at its rear end is undercut to afford a shoulder 32 which is impelled upwardly by a coil spring 33 which tends to lift the rear end of the finger, and this tendency is resisted by the provision of an adjusting screw 34 which bears against the upper side of the finger. The arrangement is such that the fingers can be individually adjusted by turning the adjusting screw so as to perfectly align the forward or acting ends of the entire group or bank of fingers.

15 The line of movement of the finger frame as a whole is in a direction transverse to the feeding movement of the metal blank, so that after the clamping plate 20 has moved down into clamping contact with the metal sheet, the fingers which theretofore have supported it may be retracted in preparation for the advance of the movable cutter bar, with the result that when the projecting end of the sheet has been severed, 25 it will fall downwardly without interference from the stop fingers.

The finger frame is given a substantially straight line movement of reciprocation in an oblique direction by the means of a cross 30 rod 35, upon which the rear ends of the straps 27 are pivoted, which cross bar has its ends entered through a pair of screw eyes 37, which in turn are entered through a cross bar 38, the ends 38^a of which are 35 forwardly bent or turned and secured to the inner faces of a pair of rearwardly extending arms 39 of a slide frame of U-shaped formation, which is provided with a cross head 40, which connects the two 40 side arms and bridges the space between the end fingers of the machine.

Each arm of the slide frame is guided between a pair of guide bars 41 secured to the inner face of the proximate end frame 45 of the machine, so that a straight line reciprocating movement will be imparted to the slide frame as a whole and to the finger frame carried thereby. The movement of reciprocation is given by the provision of a 50 pair of eccentrics 42 carried by a shaft 43, which eccentrics are provided with arms 44 which are pivoted to the arms of the slide frame.

The finger frame, being freely hinged or 55 pivoted onto the rod 35, must be additionally supported, and such support is afforded by the provision of rollers 45 which are mounted upon a shaft 46, each roller bearing against a bearing plate 47 secured to 60 the underface of the finger frame. The shaft 46 is journaled upon a pair of arms 48 which are clamped upon a rock shaft 49, the arrangement being such that by rocking the rock shaft the point of contact of 65 the rollers 45 with the bearing plates 47

may be shifted toward or away from the pivot rod 35, which will have the effect of slightly raising or lowering the finger frame as a whole, thereby providing a simple and desirable means for shifting the entire bank 70 of stop fingers up or down to the degree required for adjusting the machine to cut strips of varying width.

In order to afford these rocking movements to the rock shaft 39, the shaft is extended, see Fig. 2, beyond the left hand end frame and has clamped thereon a bell crank lever 50, the upper arm of which affords a socket 51 which receives the rear end of an adjusting screw 52 which is entered through a lug 53 on the machine frame, and the screw carries a hand wheel 54 bearing against the lug 53, so that by screwing up the wheel, the screw stem 52 will be drawn back against the tension of a spring 55 connected with a short arm 56 of the bell crank lever. By unscrewing the hand wheel, the spring will rock the shaft in the opposite direction.

The clamping plate 20 is connected by 90 strap links 57 to a cross rod 58 which is carried by slotted arms 59 mounted upon a rock shaft 60, which in turn carries an actuating arm 61 contacted by the bar 40, so that an upward recession of the bar will 95 cause the rocking of the rock shaft 60 against the tension of a spring 63 which engages the arm 64 on the end of the shaft. The movable knife blade 21 is rigidly mounted upon the bar 40, so that the knife 100 blade will partake of the entire line of movement of the bar, but the clamping plate 20, under the influence of the spring 63, will have its movement arrested as soon as it engages the end of the metal blank, which 105 it will do in advance of the arrival of the knife blade at the cutting point by reason of the amplification of movement occasioned by the greater length of the arms 59 as compared with the arm 61.

110 After the metal strips have been severed from the blank by the movable knife blade, they will fall down upon a sloping slotted runway 65 through which project a series of fingers 66 carried upon a plurality of 115 endless chains 67 which are mounted upon upper and lower sprocket wheels 69 and 70 carried by upper and lower shafts 71 and 72, respectively. The lower shaft 72 constitutes the driving shaft and has 120 mounted thereon at its left end a sprocket wheel 73, best shown in Fig. 6, which illustrates the transmission mechanism as viewed from a point inside of the machine. The sprocket wheel 73 co-operates with the 125 sprocket wheel 74 through the medium of a sprocket chain 75. The sprocket wheel 74 is mounted at the inner end of a hub 76 which carries at its outer end an upper spur gear 77 meshing with a lower spur gear 78 130

which is rigidly connected with a sprocket wheel 79 which derives power from a driving sprocket wheel 80 through the medium of a sprocket chain 81.

- 5 The hub 76 is mounted upon an upper counter shaft 82, and the lower spur gear 78 and sprocket wheel 79 are mounted upon a lower counter shaft 83, the two shafts being in parallel relation and journaled within 10 an adjustable bearing block 84 through which the shafts are extended. The inner ends of the shafts are passed through arcuate slots 85 and 86 in the adjacent wall of the frame 10, and each of the shafts is 15 threaded at its inner end to receive a nut 87, the arrangement being such that by loosening one of the nuts, the associated shaft may be moved through its arcuate slot, so that the sprocket chain may be tightened 20 or slackened to the desired degree, after which the nut can be tightened to maintain the adjustment. In this manner either or both of the chains 75 and 81 may be tightened or slackened to any desired degree. 25 The driving sprocket 80 is carried by the shaft 43 journaled within journal boxes 89 bolted to the rear portion of the end frames, and the drive shaft is driven by a pulley 90 or in any other suitable manner. 30 After the strips have been carried down along the runway 65, they are dropped into the space behind a clamping bar 91 and in front of the slot 92 through which the protruding edge of the strip is folded by the 35 advance of a crimping blade 93 driven by a cam 94, but since these details are substantially the same as are defined in the Yager patent above referred to, and since they form no part of the present invention, 40 further description is deemed unnecessary.

In operation a sheet of metal A is laid upon the platform 18 with its lower edge in contact with the protruding fingers 23 which are adjusted en banc to bring the required 45 width of the sheet below the cutting line, the fingers being severally adjusted to present an aligned surface. Thereafter the machine is started and the reciprocating frame bar 40 will advance toward the sheet and 50 as it advances the clamping plate 20 will forge ahead of the movable knife blade and contact the sheet in advance thereof.

The advance of the clamping bar and knife blade is accompanied by a recession of 55 the fingers which are secured to the same reciprocating frame, the timing being such, however, that the clamping plate will engage the sheet before the same has been released by the fingers. Thereafter a continued movement of the knife blade will 60 sever the strip which will slide down sideways until caught by a line of feeding fingers 66, which are continuously moving downwardly with the upper turns of the endless 65 chains to which the fingers are attached.

The severed strips will be fed downwardly until they are released by the fingers and fall to the crimping point at which they are forced through the slot by the crimping blade and released from the machine. 70

The method of adjusting the fingers en banc by means of the rock shaft 49 carrying the rollers 45 is one which not only affords a ready and easy adjustment, but also furnishes a roller bearing for the finger frame in all positions of adjustment and involves a marked simplification and improvement over the mechanism set forth in the Yager patent. Furthermore, by mounting the finger frame directly upon the reciprocating frame, adequate means are provided for the coordination of the finger and knife movements, and a simplification of the construction is effected as compared with that set forth in the prior patent above mentioned. 80 85

I claim:

1. In a machine of the class described, the combination of a frame provided with a support for a blank to be severed, a plurality of stop fingers normally projecting beyond said support, a frame upon which said fingers are mounted, a cutting knife, means for retracting the finger frame and fingers concurrently with the advance of the cutting knife, means for adjusting the fingers individually with respect to the finger frame, and means for adjusting the finger frame to position the entire bank of fingers, with relation to the cutting line of the knife substantially as described. 90 95

2. In a machine of the class described, the combination of a frame provided with a support for a blank to be severed, a plurality of stop fingers normally projecting beyond said support, a frame upon which said fingers are mounted, a cutting knife, means for retracting the finger frame and fingers concurrently with the advance of the cutting knife, means for adjusting the fingers individually with respect to the finger frame, means for adjusting the finger frame to position the entire bank of fingers, said means including a rock shaft, arms carried by the rock shaft, and bearing members carried by said arms and adapted to be swung to varying positions to effect adjustment of the finger frame, substantially as described. 100 105 110 115

3. In a machine of the class described, the combination of a frame provided with a support for the blank to be severed, a plurality of stop fingers normally projecting beyond said support, a pivoted frame upon which said fingers are mounted, a cutting knife, means for retracting the finger frame and fingers concurrently with the advance of the cutting knife, means for adjusting the fingers individually with respect to the finger frame, and means for adjust- 120 125 130

ing the finger frame to position the entire bank of fingers, with relation to the cutting line of the knife substantially as described.

4. In a machine of the class described, 5 the combination of a frame provided with a support for the blank to be severed, a plurality of stop fingers normally projecting beyond said support, a pivoted frame upon which said fingers are mounted, a cutting knife, means for retracting the finger frame and fingers concurrently with the advance of the cutting knife, means for adjusting the fingers individually with respect to the finger frame, means for adjusting the 10 finger frame to position the entire bank of fingers, said means including a rock shaft, arms carried by the rock shaft, and bearing members carried by said arms and adapted to be swung to varying positions to effect adjustment of the finger frame, substantially as described.

5. In a machine of the class described, the combination of a frame provided with a feeding platform, a stop finger normally protruding beyond the plane of the feeding 25 platform, a finger frame carrying the finger, fixed and movable cutters, a reciprocating frame carrying the movable cutter and the finger frame, and means for imparting 30 movements of reciprocation to the reciprocating frame, substantially as described.

6. In a machine of the class described, the combination of a frame provided with a feeding platform, a plurality of stop fingers 35 normally protruding beyond the plane of the feeding platform, a finger frame carrying the fingers, fixed and movable cutters, a reciprocating frame carrying the movable cutter and the finger frame, means for imparting 40 parting movements of reciprocation to the reciprocating frame, means for adjusting the stop fingers individually and with respect to the finger frame, and means for adjusting the finger frame to vary the width of the 45 strip to be severed, substantially as described.

7. In a machine of the class described, the combination of a frame provided with a feeding platform, a plurality of stop fingers 50 normally protruding beyond the plane of the feeding platform, a finger frame carrying the fingers, fixed and movable cutters, a reciprocating frame carrying the movable cutter and the finger frame, means for imparting 55 movements of reciprocation to the reciprocating frame, means for adjusting the stop fingers individually and with respect to the finger frame, and means for adjusting the finger frame to vary the width of the strip to be severed, said means including a 60 rock shaft, arms carried by the rock shaft, and bearing members carried by said arms and adapted to be swung to varying positions to effect adjustment of the finger frame, substantially as described.

8. In a machine of the class described, the combination of a main frame provided with a feeding platform adapted to receive a sheet of metal, a stop finger normally protruding beyond the plane of the platform, a reciprocating frame slidably mounted within the main frame and carrying a cutter blade, a finger frame pivoted to the reciprocating frame and carrying the finger, an anti-friction roller bearing against the underside of the pivoted finger frame at a point distant from the pivotal mounting therefor, and means for adjusting the position of the anti-friction roller toward and from the pivotal mounting to adjust the position of the stop finger, substantially as described. 75

9. In a machine of the class described, the combination of a main frame provided with a feeding platform adapted to receive a sheet of metal, a stop finger normally protruding beyond the frame of the platform, a reciprocating frame slidably mounted within the main frame and carrying a cutter blade, a finger frame pivoted to the reciprocating frame and carrying the finger, an anti-friction roller bearing against the underside of the pivoted finger frame at a point distant from the pivotal mounting therefor, means for adjusting the position of the anti-friction roller toward and from the pivotal mounting to adjust the position of the stop finger, said means including an adjustable rock shaft, and an arm carried thereby upon which the anti-friction roller is mounted, substantially as described. 80

10. In a machine of the class described, the combination of a main frame provided with a platform for supporting a sheet of metal, a reciprocating frame movable in transverse relation to the plane of said platform, a movable cutter blade carried by the reciprocating frame, a plurality of stop fingers normally protruding beyond the plane of the platform, a finger frame pivoted to the reciprocating frame, means for imparting reciprocating movements to the reciprocating frame, and means for swinging the finger frame on its pivot to adjust the entire bank of stop fingers with respect to the cutting line, substantially as described. 95

11. In a machine of the class described, the combination of a main frame provided with a platform for supporting a sheet of metal, a reciprocating frame movable in transverse relation to the plane of said platform, a movable cutter blade carried by the reciprocating frame, a plurality of stop fingers normally protruding beyond the plane of the platform, a finger frame pivoted to the reciprocating frame, means for imparting reciprocating movements to the reciprocating frame, means for swinging the finger frame on its pivot to adjust the entire bank of stop fingers with respect to the cutting line, and means carried by the finger frame for effect- 100

ing individual adjustment of each of the fingers, substantially as described.

12. In a machine of the class described, the combination of a main frame provided with a feeding platform for supporting a sheet of metal, a movable cutter blade adapted to sever strips from the sheet, a plurality of stop fingers normally protruding beyond the plane of the feeding platform, a finger frame upon which the fingers are individually fulcrumed at an intermediate point, and adjusting devices for each finger at the rear end thereof for swinging each finger upon its fulcrum point, means for advancing and retracting the finger frame and fingers, and an adjustable bearing for the finger frame for effecting adjustment of the entire bank of fingers, substantially as described.

13. In a machine of the class described, the combination of a main frame provided with a feeding platform for supporting a sheet of metal, a movable cutter blade adapted to sever strips from the sheet, a plurality of stop fingers normally protruding beyond the plane of the feeding platform, a finger frame upon which the fingers are individually fulcrumed at an intermediate point, adjusting devices for each finger at the rear end thereof for swinging each finger upon its fulcrum point, means for advancing and retracting the finger frame and fingers, a pivotal mounting for the finger frame, a roller bearing for the finger frame in advance of said pivotal mounting, and means for moving said roller bearing toward and from the pivotal mounting to effect adjustments of the entire bank of stop fingers with respect to the cutting line, substantially as described.

14. In a machine of the class described, the combination of a main frame provided with a support for a metal blank, a plurality of stop fingers normally protruding beyond the plane of said support, a finger frame upon which the fingers are individually pivoted, adjusting means at the rear end of each finger for tilting the fingers individually upon their fulcrum points, a pivotal mounting for the finger frame, means for imparting movements of advance and recession to said pivotal mounting, an adjustable bearing for the finger frame in advance of said pivotal mounting and adapted by adjustment to effect an adjustment of the entire bank of fingers, substantially as described.

15. In a machine of the class described, the combination of a main frame provided with a support for blanks to be severed, a plurality of stop fingers normally protrud-

ing beyond the plane of said support, a mounting for said fingers, means adapted to cause movements of advance and recession to said mounting, a movable cutter blade, a reciprocating frame upon which said cutter blade is mounted, means for imparting reciprocation thereto, a clamping plate, a rock shaft provided with a relatively long arm connected with said clamping plate, and a short arm on said shaft engaged by said reciprocating frame for effecting an accelerated movement of the clamping plate with respect to the cutter blade, substantially as described.

16. In a machine of the class described, the combination of a main frame provided with a support for blanks to be severed, a plurality of stop fingers normally protruding beyond the plane of said support, a mounting for said fingers, means adapted to cause movements of advance and recession to said mounting, a movable cutter blade, a reciprocating frame upon which said cutter blade is mounted, means for imparting reciprocation thereto, a clamping plate, a rock shaft provided with a relatively long arm connected with said clamping plate, a short arm on said shaft engaged by said reciprocating frame for effecting an accelerated movement of the clamping plate with respect to the cutter blade, and a spring connected with said rock shaft for holding the short arm under tension in engagement with the reciprocating frame, substantially as described.

17. In a machine of the class described, the combination of a main frame provided with a support for blanks to be severed, stop fingers for temporarily arresting the advance of the blank, a movable cutter for severing strips from the blank, a runway below the cutter, a plurality of endless feeding chains located beneath the runway and provided with lines of stop fingers extending through the runway, sprockets upon which said chains are mounted, shafts carrying said sprockets, one of the shafts being provided with a driving sprocket, a main power shaft carrying a primary sprocket, a pair of counter shafts located between the power shaft and the driving shaft for the feed chains, a bearing block for said counter shafts adapted to be swung around either shaft as a center, intermeshing gears carried by said counter shafts, a driving sprocket carried by one of the counter shafts, and a driven sprocket carried by the other counter shaft, and primary and secondary transmission sprocket chains co-acting with the sprockets, substantially as described.

JOHN W. DIXON.
